UNITED STATES PATENT OFFICE.

WILLIAM L. KANN, OF PITTSBURGH, PENNSYLVANIA.

METHOD OF GRINDING AND SMOOTHING GLASS.

1,075,107.

Specification of Letters Patent.

Patented Oct. 7, 1913.

Application filed October 26, 1912. Serial No. 727,978.

To all whom it may concern:

Be it known that I, WILLIAM L. KANN, a citizen of the United States, and resident of Pittsburgh, Allegheny county, State of Pennsylvania, have invented certain new and useful Improvements in Methods of Grinding and Smoothing Glass, of which the following is a specification.

This invention relates to a method and machines for grinding and smoothing plate glass and has particular reference to the method and means for handling the sand or abrading material and grading the same. Heretofore the practice has been to apply 10 the sand used in such machine in as coarse a condition as was possible to obtain it and then use six to eight finer grades until the application of the final grade leaves the glass almost polished. As a matter of necessity and 15 economy the sand used and crushed and ground down in the process of rough grinding is later used again for the finer grinding. Generally the grinding machine has a ditch arranged about its circumference into 20 which the sand and water which have been used in the machine are thrown from the grinding tables by centrifugal force. The heavy sand deposits immediately in this circular ditch and is returned to the table as 25 long as there is enough coarse grit in it to do heavy grinding, while the finer grades flow out of the ditch into a main ditch from 30 which they are flowed into a series of collecting pits where they are graded according to 35 their coarseness and the resultant material is used in all machines for subsequent final grinding. In such a system it is usual to connect the discharge from all machines into one set of grading pits. The fine sand or 40 grading pits are divided by partitions and as the sand and water flows into the pits the grades which will be deposited by gravity into each pit is determined by the space 45 between the partitions and the height thereof. The number of machines varies greatly; 50 each machine varies in its process from rough grinding to fine smoothing. Sometimes all of the machines are running and sometimes only part, so it can be readily seen that the 55 amount of sand and the amount of water used with the sand is a constantly varying quantity, as a consequence of which the grades of sand deposited in the different settling pits will vary with the fluctuating flow of the water, the result being that when the flow is slowest there is considerable finer

sand deposited in the pits for the coarse sand, and when the flow of the water is swift the reverse action takes place; that is, there is considerable of the rough sand carried over into the pits intended for the finer sand. The first action is not very harmful, but it decreases the efficiency of the coarser grades. The second action, however, is very harmful as the mixing of the coarse grades with the finer grades scratches the glass and retards the finishing making it necessary to do the operation over again, in part or whole, as only glass which is uniformly properly smoothed will make a desired fine polish on 70 plate or other glass.

In the present application the method of utilizing the coarse sand and the used sand differ from the usual practice and consists broadly in feeding a sufficient amount of new sand to a hopper or other suitable receptacle convenient to the grinding table and cutting off the supply of new sand. The batch of new sand in the hopper is then used in the same and only one machine for 75 both the grinding and smoothing operations, no new sand being mixed with the old and by such a continuous operation a predetermined or fixed result is assured each time. By the arrangement of this invention the 80 sand is, in the process of grinding, ground finer and finer and graded until the glass is smoothed ready for polishing, when the sand is too fine for further use and may be 85 flowed off. The grading of the sand as it is 90 ground and reground in the machine is done separately for each batch of sand and each machine, and the head of water and other factors which usually vary in present processes are kept constant, whereby much better and more uniform results are obtained.

To properly carry out the invention and attain the above and other objects, the arrangement of apparatus as herein described is provided.

In the drawings—Figure 1 illustrates a plan view of an installation for grinding, smoothing and polishing glass, and comprises two independent machines; Fig. 2 is a sectional view through the sand pits showing the grinding, smoothing and polishing machines in elevation. Fig. 3 is a detail, foreshortened view of the tele copic pulsator or elevating device.

In the illustration, 10 and 11 represent 110 two rotatable grinding tables or platforms of the usual or any preferred construction,

and of which there may be any number. The tables 10 and 11 support the glass plates and have the rotating pairs of rubbing or grinding disks 12 and 13 arranged to coöperate therewith in the well known manner, as is clearly shown. The rubbing disks 12 and 13 are supported for rotation in frames 14 and 15 arranged to extend over the grinding tables 10 and 11. A ditch or gutter 17 is provided beneath each of the tables 10 and 11 and extends beyond the circumference of the tables a short distance to catch the sand as it is thrown from the tables by centrifugal force. Suitable operating mechanism for these parts (not shown) may be provided. New unused sand from a supply or storage bin 18 is arranged to be discharged through a screen 20 of suitable mesh into a new sand pit 19 which also holds a supply of water. The pumping mechanism which extends into the pit or receptacle 19 comprises a stationary tubular portion 21 supported at the top of the well and having the discharge branches 22. As shown in Fig. 3, telescopically connected to the tube 21 there is a lower movable pipe 23 which may be raised and lowered into section 21 so as to adjust its position with reference to the bottom of the pit 19. Extending down through the section 21 and connected to spiders 230 and 231 rigidly mounted at opposite ends of the movable member 23 and extending almost to the lower end of the section 23 there is a compressed air pipe 24 which at its upper end is flexibly connected to a compressed air supply 25. In operation the compressed air is discharged into the lower portion of the elevator tube and by creating an upward current therein, will cause the sand and water to rise and discharge through the outlet pipe 22. The pipe 23 is raised and lowered by moving the pipe 24 by means of a counterbalance weight 26 which is connected to the upper end of the compressed air pipe 24. The latter and the lower section 23 of the telescopic water and sand elevator are maintained at any desired adjustment. The elevating device is separated from the inlet thereto by a vertical partition 27 which divides the pit 19 into two compartments. The partition is adjustable so that it can be moved into several positions as shown in dotted lines, whereby the sand may be graded and properly cleaned before elevating. By introducing water under pressure into the pit 19, the new sand therein is first washed and cleaned of any muck, loam or foreign matter, the slimes and foreign matter flowing off into ditch 44. This is accomplished by the upward pressure and as a result the new sand is fully effective and clean. The lower end of the partition may be adjusted to any height above the bottom of the pit 19. The movable partition is very

essential and makes the device practicable since it is then possible to control the speed of the rising current and by that means control and classify the sand contained in the stream according to its weight or specific gravity. This is due to the variation of the cross section of the pit compartment in which the elevator device is located. The clean sand delivered from the discharge pipe 22 is conveyed through pipes 28 to a new sand hopper 29 or 29' arranged in any convenient position above the tables 10 and 11 to deliver the sand to the latter. When sufficient new sand has been delivered to grind the glass level the new sand supply is turned off and the sand used in coarse grinding is reused. Any excess of new sand runs over into the receptacle 30 and is returned to the pit 19 by the pipe 31. The sand discharging on to the tables 10 and 11 in its grinding action is thrown outwardly and with the water, discharges into the ditch 17 and 17' from which it is delivered through screens 32, 32' into separate pits 33 and 34, similar in construction to the pit 19. Each of the pits 33 and 34, and as many more as there are grinding machines, are provided with an arrangement for elevating sand therefrom, and movable partitions as is provided in the pit 19.

The elevating device 35 located in the pit 33 has its discharge end connected to the pipe 36 which delivers sand raised from the pit 33 into a hopper 37 located above the table 10. A hopper 37' above the table 11 receives sand from the pit 34 through the elevating mechanism 38 in the same manner. The hoppers 29 and 37 are arranged to discharge into a hopper 46 which delivers the sand or abrasive to the grinding, smoothing and polishing mechanism. The hopper 37 is connected by a trough 38 with a series of grading hoppers 39, 40, 41 and 42 the last of which has a slime overflow connection 43 with the waste flue 44. The grading hoppers each have a valved connection with a pipe 47 which discharges into hopper 46 for delivery to the grinding devices. In the successive grinding of the plate only the coarser materials are used over and over again and as a consequence, become gradually finer and are perfectly graded in the grading hoppers 39 to 42 so that finally only the fine material without any coarser particles will be available for fine grinding. The slimes are therefore continually separated from the coarser particles in each cycle as the sand is circulated through the apparatus. The movable partitions 33' and 34' in the drainage pits 33 and 34 assist in grading the sand and by reason of the fact that a constant head of water is maintained in the grading hoppers and pit an effective grading of the sand is guaranteed. All excess of water in the wells 33 and 34 is con-

ducted to the waste flume 44 by the overflow connections 45 and 45', thereby maintaining a constant head of water for grading purposes. To maintain the stream of water 5 through the elevating devices 35 and 38 uniform the air supply used in elevating the water is kept at a constant pressure. Similar grading hoppers 39', 40', 41' and 42' are provided above the table 11 and a slime 10 overflow connection 43' discharges into the waste 44.

By reason of the constant or fixed water and air pressure and telescopic elevating device used in this combination the grading of 15 the abrasive can be absolutely controlled. When no more sand is required out of either pits 19, 33 or 34 in the operation and only water is required to finish the grades in the 20 various hoppers, the telescopic member of the elevating device may be lifted away from the sand contact in the pits while the operation is going on, and without intermission.

In the arrangement shown each grinding 25 and smoothing machine is a unit complete in itself in which the whole process of rough grinding, fine grinding, smoothing and grading of the material is carried on. Each machine is independent of the action of its 30 neighbors and by applying a constant head of water, the grading of the abrasive material both in the pump pits and in the fine sand supplying boxes can be predetermined and regulated. The elevating device, movable 35 partition, the fixed head of water and the fixed air pressure make it possible to absolutely regulate the grading of the sand and thereby permits the use of the sand from coarse grinding down to smoothing, 40 or until the sand has lost its further usefulness.

What I claim is:

1. The method of grinding and smoothing plate glass which consists in placing the 45 rough glass in a grinding apparatus, supplying new coarse sand and water to said apparatus until a sufficient quantity of such sand has been supplied to effect the rough grinding of the glass, circulating the used sand through an apparatus for separating 50 the slimes and back to the grinding appa-

ratus, whereby finer grinding may be effected, and repeating this operation with the same original batch of sand until the same is reduced to a fine grade and the 55 glass is provided with a comparatively smooth surface.

2. The method of grinding plate glass which consists in placing the rough plates of glass in a grinding apparatus, feeding 60 new coarse sand and water to said apparatus until a sufficient quantity of such sand has been supplied to effect the rough grinding, circulating the used sand away from and back to the grinding apparatus repeatedly, 65 and in the course of each cycle separating out the slimes and the finer particles of sand, whereby the rough and smooth grinding of the glass may be completed with a single and the same batch of sand. 70

3. The method of grading and smoothing glass which consists in placing the rough glass in a suitable grinding mechanism, circulating water and sand to and from the grinding mechanism repeatedly, 75 separating out the slimes and grading the remaining sand while maintaining a constant head or pressure of water.

4. The method of grinding and smoothing glass which consists in placing the rough 80 glass in a grinding machine, feeding new coarse sand and water to said machine until a sufficient quantity of such sand has been supplied to effect the rough grinding, shutting off the supply of new sand, circulating 85 water and the used sand away from and back to the grinding machine repeatedly, and in the course of each cycle separating out the slimes and grading the finer particles of sand while maintaining a fixed 90 head or pressure of water to facilitate the grading of the sand whereby the entire grinding operation may be completed in a single machine and with a single batch of sand. 95

In testimony whereof I affix my signature in presence of two witnesses.
